UNITED STATES PATENT OFFICE

SAMUEL MARCUS, OF BELLE HARBOR, NEW YORK, ASSIGNOR TO MARGON CORPORATION, OF NEW YORK, N. Y., A CORPORATION OF NEW YORK

DOLL AND MOUTH SET FOR SAME

Application filed October 21, 1932. Serial No. 638,884.

This invention relates to dolls, particularly dolls having a tongue or/and teeth set at the mouth opening thereof, and more especially to the tongue or/and teeth set, which I may 5 designate generally as a mouth set, for such dolls.

In order to enhance the realism of more expensive and better grade of dolls, it is customary to provide the doll's head with a 10 mouth opening and to subsequently affix in back of the mouth opening a mouth set which may comprise merely a simulated tongue and mouth cavity or which may be further improved by the addition of simulated 15 teeth. The primary and general object of the present invention is to improve such mouth sets both as regards the tongue member and the teeth associated therewith, with a view to improving the appearance and realism of 20 the doll.

The tongue elements have heretofore consisted of a forwardly projecting tongue-simulating member disposed directly in or behind the mouth opening. Examples of 25 this form of construction are illustrated in my prior Patents 1,689,925, 1,744,129, and 1,758,164. While the mouth sets disclosed in said patents represent substantial improvements in the art and serve to greatly 30 improve the appearance of a doll's head provided with the same, I have since discovered that the attractiveness and realism of the doll may be even further enhanced by altering the shape of the mouth or/and tongue 35 member. Specifically, the tongue members as heretofore constructed give the doll a full-moutherd appearance and emphasize the presence of the tongue in a somewhat unnatural manner. I have experimented with various 40 shapes, positions, and dimensions of such tongue members, and have finally found that the most natural and attractive simulation of mouth and tongue is obtained by entirely omitting any particular forwardly project- 45 ing tongue element located directly in or behind the mouth opening, and instead closing the mouth opening with a trough-like member of preferably V-shaped cross-section, so that the tongue is represented only by the 50 lower face of the trough, thus simulating the

upper surface of the tongue lying in normal position within the mouth cavity, rather than projecting out of or at the mouth opening in a rather too conspicuous manner.

Further features of the present invention 55 center about the teeth, which may optionally be used in association with the aforesaid mouth member, and corresponding objects of my invention are to reduce the cost and increase the realism of such teeth. It has al- 60 ready been proposed to make the teeth out of sheet celluloid, thereby giving the same a permanent white color not subject to chipping or other difficulties of painted sheet metal teeth. However, relatively heavy 65 gauge sheet celluloid must be used, and even then the teeth do not have the rounded relatively thick appearance of natural teeth. In accordance with a further feature and object of the present invention, a thin gauge cellu- 70 lid is used which is punched and stamped into a hollow or shell-like configuration, the resulting rearwardly extending flanges or edges serving to give the teeth a solid appear- 75 ance which is both natural and desirable, and further serving to rigidify and strengthen the teeth. The use of thin sheet celluloid at the same time reduces the cost of the teeth.

Still another object of the present invention resides in the provision of means on the 80 mouth set for gripping and supporting the teeth; the construction of such means in a manner making it possible to use the mouth set with either no teeth, or upper teeth alone, or lower teeth alone, or both upper and lower 85 teeth, a single standard tongue being used for each of these alternative forms; and the further modification of the attaching means holding the tongue and teeth elements together, whereby the parts are relatively 90 yieldable or self-adjustable so that they will accommodate themselves to the configuration of the interior of the head to which the mouth set is applied.

To the accomplishment of the foregoing 95 and such other objects as will hereinafter appear, my invention consists in the tongue or/and teeth elements and their relation one to the other and to the doll's head in which they are mounted, as hereinafter are more 100

particularly described in the specification and sought to be defined in the claims. The specification is accompanied by a drawing in which:

5 Fig. 1 is a front elevation of a doll's head provided with a mouth set and embodying features of the present invention;

Fig. 2 is a vertical section taken in the plane of the line 2—2 in Fig. 1;

10 Fig. 3 is a front elevation of a mouth set having no teeth;

Fig. 4 is a front elevation of a mouth set provided with only upper teeth;

15 Fig. 5 is a horizontal section taken in the plane of the line 5—5 in Fig. 2;

Fig. 6 is a front view of a mouth set provided with both upper and lower teeth;

20 Fig. 7 is a horizontal section taken through the teeth in the plane of the line 7—7 in Fig. 4; and

Fig. 8 is a plan view of the tongue member prior to embedding its mounting tang in the head.

25 Referring to the drawing and more particularly to Figs. 1, 2, and 5 thereof, the invention comprises a doll's head 12 which may be molded in the conventional manner and which therefore probably need not be described in detail here. The head is provided with a mouth opening 14 behind which there is affixed a mouth set generally designated 16, said mouth set preferably serving to completely close the mouth opening 14.

30 The mouth set 16 may or may not be provided with teeth, a form without teeth being shown in Fig. 3, and if provided with teeth either upper teeth may be used alone, as is illustrated in Figs. 1, 2, and 4, or lower teeth may be used alone (not illustrated), or upper 35 and lower teeth may be used, as is illustrated in Fig. 6. The most important single feature of the present invention centers about the construction of the mouth set irrespective of the inclusion or omission of teeth, and this feature will first be described with particular reference to Fig. 3 of the drawing.

40 Adverting to that figure, the mouth set 16 comprises a generally trough-like member 18 which is preferably V-shaped in cross-section 50 and which extends in a generally horizontal direction, the closed side of the trough extending to the rear, and the open side of the trough facing the front of the doll's head, as is best shown in Fig. 2. The open side of the trough 18, as outlined for example by the edge 20, is dimensioned to approximately fit the mouth opening 14 of the doll's head, thereby closing the mouth opening. This trough-like member 18 is, of course, colored red and simulates the mouth cavity. No central and distinct tongue member such as has heretofore been employed is used, but instead the lower face 22 of the trough 18 simulates the upper surface of the tongue of the doll. This simplified arrangement gives the doll a far more

realistic and natural appearance than the heretofore conventional arrangements in which a distinct and forwardly projecting tongue member has been positioned directly in the mouth opening.

70 For convenience, the mouth member 16 is enlarged and arranged to fit flat against the wall of the head around the mouth opening, the trough-like mouth cavity 18 being formed at the center of the enlarged mouth member.

75 In effect, the trough 18 is provided with a surrounding skirt or flange 22. This flange or facing is curved convexly toward the front of the doll's head, forming a smooth rounded surface dimensioned to fit within the head at the mouth opening. By coloring the entire member red, it is not essential to position the mouth set precisely or critically in relation to the mouth opening. The convex shape of the skirt 16 makes it possible for the rear edge of the trough 18 to be relatively straight while providing the forward or open face of the trough with a maximum width at the center and diminishing width toward each side, conforming to the generally elliptical 80 shape of the mouth opening 14. This feature of the construction is most clearly evident from an inspection of Fig. 5 of the drawing.

85 The mouth or tongue member 16 is preferably provided with means formed integrally therewith for mounting the same within the doll's head. In the particular case here illustrated, the said means comprises a pair of sidewardly extending arms 26 each provided at its outer extremity with a tang or spur 28. 90 The arms 26 may, if desired, be channeled, as indicated at 30, in order to strengthen and rigidify the same. These arms initially extend rearwardly as well as outwardly, in a manner best indicated in Fig. 8, but when the mouth set is mounted in the head the arms are forced forwardly by a tool and are thereby embedded in the material of the head, as is best shown in Fig. 5. The angle of the tangs is preferably so adjusted, as will be evident from a comparison of Figs. 8 and 5, that upon bending of the arms forwardly the prongs are 95 so embedded in the head that they converge forwardly or extend toward one another, thereby mutually locking themselves in the material of the head, and forming a permanent anchorage or mounting for the mouth set in the head.

100 The tongue member 16 is preferably further provided with means adapted to receive and hold teeth in proper relative position to the mouth opening. The requirements for various dolls differ, and accordingly the said means are so designed that the addition of teeth is entirely optional. Thus, referring to Fig. 3, the tongue member is provided at its upper and lower edges with a generally 105 T-shaped projection comprising, in effect, a lug 32 and sidewardly projecting fingers 34. In order to make the entire unit somewhat 110

flexible and adaptable to the doll in which it is inserted, the skirt 22 is preferably cut away or narrowed at the base of the lugs 32. In this manner the lugs may be provided with 5 a minimum waste of material, for they are largely formed from the material of the skirt 22; also, the teeth are supported relatively near the mouth opening. If no teeth are employed, as in the case of the unit shown in 10 Fig. 3, the incised condition of the metal 70 no way affects the appearance of the tongue member when mounted in the head, and at the same time permits the curvature or convexity of the member to adapt itself to the 15 inner wall of the particular head in which it is mounted.

In Figs. 2 and 4 the mouth set heretofore described is shown modified by the addition of upper teeth. The teeth are formed from 20 a thin sheet of celluloid which is stamped and pressed into a hollowed or shell-like configuration simulating a pair of adjacent front teeth 40 provided with an upwardly projecting arm 42. The manner in which the 25 thin celluloid material is dished or hollowed to simulate the teeth may best be understood by reference to Fig. 7 in which it will be seen that the sheet material is flanged at its edges 44 and is indented at its center 46, thereby 30 giving the teeth a well-rounded and relatively thick or heavy appearance closely simulating that of natural teeth. This form of construction is a great improvement over the use of flat stampings of celluloid even if thick 35 celluloid is used, and at the same time economy results because of the use of thin celluloid. The arrangement is also a great improvement over any attempted stamping or 40 shaping of metal which must be painted or lithographed white, because with celluloid the white color is permanent and indestructible and cannot be marred or scratched. Still another advantage of the use of thin celluloid, shaped as described, resides in the fact 45 that the upwardly extending arm 42 may be left flat and therefore relatively flexible. This contrast of the shaping of the teeth 40 while leaving the arm 42 flat is evident from an inspection of Fig. 2.

50 To secure the teeth on the tongue member 16 it is simply necessary to place the arm 42 over the lug 32 and thereupon to bend the sidewardly extending fingers 34 forwardly and around the arm 42 in a manner clearly 55 evident from an inspection of Fig. 4 of the drawing. A special tool or fixture may be provided for this purpose, thereby permitting the teeth to be added to the tongue member under rapid machine production conditions. 60 It will be understood that the number of teeth provided on the teeth set may be varied so that more or less than the two teeth shown may be used.

If the doll is to have only lower teeth, it 65 is simply necessary to reverse the unit shown

in Fig. 4 when mounting the same in the doll's head. However, it is customary to use a somewhat smaller size of tooth when simulating lower teeth, and consequently a different size of tooth set may be used. 70

If the doll is to be provided with both upper and lower teeth, the construction will take the form shown in Fig. 6 in which the fingers 34 of both the upper and lower sides of the tongue member are bent around and 75 secure sets of teeth, the lower set of teeth preferably being somewhat smaller than the upper set of teeth. Here again, although two teeth have been shown in each of the sets, it is possible to vary the number of teeth and 80 to relatively vary the number of teeth shown at the top and bottom of the mouth. In every case the mode of attachment of the mouth set within the doll's head is unchanged.

It has already been mentioned that the 85 arm 42 of the teeth set is preferably left unchanged and relatively flexible. This is desirable because it permits a flexing or bending of the teeth set when mounting the entire 90 unit in the doll's head, the teeth being pressed against the inside of the mouth opening and being forced snugly into contact therewith, and the entire mouth set accommodating itself as a whole to the configuration of the 95 inferior of the head at the mouth opening. 100

It will be understood that in use the upper 105 side of the channel 18 is cast in shadow and is practically invisible, while the lower side 22 of the channel tends to reflect light and simulates a tongue in normal position in back of the lower teeth. It will therefore be appreciated that in one aspect the present invention centers about the provision of a tongue member having a relatively rounded forward edge and extending entirely across the width 110 of the mouth and sloping upwardly and rearwardly, which tongue member instead of being located directly in or in back of the mouth opening, is located just below the mouth opening. In effect there is no simulation 115 of the end of a protruding tongue, but rather merely a simulation of the upper surface of a tongue lying well down in the mouth in normal position. From this viewpoint it is not essential that the tongue element include a channel such as I have specifically 120 described, nor, in fact, is it essential to use the upper part of the mouth member at all, although this is desirable in order to blank off or close the mouth opening. The improvement in appearance resulting from thus 125 relatively inconspicuously locating the tongue in lowered and retracted position is very remarkable and is rather difficult to portray in a drawing.

It is believed that the mode of constructing and using the mouth set of my present invention, as well as the many advantages thereof, will be apparent from the foregoing 130 detailed description. It will also be apparent

that while I have shown and described my invention in preferred forms, many changes and modifications may be made in the structures disclosed, without departing from the spirit of the invention, defined in the following claims.

I claim:

1. An artificial tongue or mouth element for a doll's head having a mouth opening, 10 said element comprising a generally trough-like member the open side of which is adapted to fit in back of the mouth opening, with the trough extending horizontally from one side of the mouth opening to the other, and additional mounting means so designed as to support the same at the mouth opening with the open side of the trough facing the mouth opening.

2. An artificial tongue or mouth element 20 for a doll's head having a mouth opening, said element comprising a generally trough-like member of V-shaped cross-section arranged to extend from one side to the other directly in back of the mouth opening, and additional 25 mounting means so designed as to support the same at the mouth opening with the open side of the trough facing the mouth opening.

3. The combination with a doll's head having a mouth opening, of an artificial 30 tongue or mouth element comprising a generally trough-like member of V-shaped cross-section extending from one side to the other directly in back of the mouth opening and serving to close said mouth opening, and additional 35 mounting means so designed as to support the same at the mouth opening with the open side of the trough facing the mouth opening, the lower surface of said member simulating the upper surface of a tongue 40 within the mouth.

4. An artificial tongue or mouth element for a doll's head, said mouth element comprising a unitary piece of sheet metal punched and pressed into a generally convex 45 shape adapted to fit closely against the front interior wall of the head at the mouth opening, the entire central portion of said plate being pressed rearwardly to form a trough extending from one side to the other of the plate, the forward or open side of said trough being dimensioned to approximately fit the mouth opening in the doll's head.

5. An artificial tongue or mouth element for a doll's head provided with a mouth opening, said mouth element comprising a unitary piece of sheet metal punched and pressed into a generally convex shape adapted to fit closely against the front interior wall of the head at the mouth opening, the entire 55 central portion of said plate being pressed rearwardly to form a V-shaped trough extending from one side to the other of the plate, the forward or open side of said trough being dimensioned to approximately fit the mouth opening in the doll's head, and said

plate being further provided with arms having tangs or spurs on the ends thereof for securing said mouth element to the wall of the head.

6. An artificial tongue or mouth element 70 for a doll's head provided with a mouth opening, said mouth element comprising a unitary piece of sheet metal punched and pressed into a generally convex shape adapted to fit closely against the front interior wall of the head at the mouth opening, the entire central portion of said plate being pressed rearwardly to form a V-shaped trough extending from one side to the other of the plate, the forward or open side of said trough being dimensioned to approximately fit the mouth opening in the doll's head, the said plate being further provided with upwardly and downwardly extending T-shaped lugs, 75 the plate being cut away at the base of said lugs in order to permit bending or adjustment of said lugs.

7. An artificial tongue or mouth element 80 for a doll's head provided with a mouth opening, said mouth element comprising a unitary piece of sheet metal punched and pressed into a generally convex shape adapted to fit closely against the front interior wall of the head at the mouth opening, the entire central portion of said plate being pressed rearwardly 85 to form a V-shaped trough extending from one side to the other of the plate, the forward portion or open side of said trough being dimensioned to approximately fit the mouth opening in the doll's head, said plate being provided with means for securing the same 90 within the head, and being further provided with means for securing artificial teeth thereto.

8. The combination with a doll's head having a mouth opening, of an artificial tongue or mouth element comprising a unitary piece of sheet metal punched and pressed into a generally convex shape fitting closely against the front interior wall of the head at the mouth opening, the central portion of said plate being pressed rearwardly to form a V-shaped trough extending from one side to the other of the plate, the forward or open side of said trough being dimensioned to approximately fit the mouth opening in the doll's head and serving to close said opening.

9. An artificial tongue or mouth element 110 for a doll's head, said mouth element comprising a unitary piece of sheet metal punched and pressed into a generally convex shape adapted to fit closely against the front interior wall of the head at the mouth opening, the entire central portion of said plate being pressed rearwardly to form a trough extending from one side to the other of the plate, the forward or open side of said trough being dimensioned to approximately fit the mouth opening in the doll's head, a tooth set 115 consisting of celluloid shaped to simulate teeth, 120

and means on said plate for holding said tooth set.

10. An artificial tongue or mouth element for a doll's head, said mouth element comprising a piece of sheet metal adapted to fit closely against the front interior wall of the head at the mouth opening, the entire central portion of said plate being pressed rearwardly to form a trough extending from one side to the other of the plate, the forward or open side of said trough being dimensioned to approximately fit the mouth opening in the doll's head, a tooth set consisting of thin white celluloid punched and stamped into the form of a plurality of adjacent teeth and a supporting arm, the teeth being stamped into a hollow or shell-like configuration in order to give the same a natural rounded appearance with substantial depth or thickness, said plate being provided with upwardly and downwardly projecting lugs at least one of which has fingers bent around and gripping the aforesaid arm of the tooth set.

15. An artificial tongue or mouth element for a doll's head, said mouth element comprising a piece of sheet metal punched and pressed

into a generally convex shape adapted to fit closely against the front interior wall of the head at the mouth opening, the central portion of said plate being pressed rearwardly to form a V-shaped trough extending from one side to the other of the plate and dimensioned to approximately fit the mouth opening in the doll's head, said plate being provided with a pair of sidewardly projecting arms having tangs or spurs on the ends thereof, and being further provided with upwardly and downwardly projecting lugs each having fingers bent around and gripping the supporting arm of a tooth set, each of said tooth sets consisting of thin white celluloid punched and stamped into the form of a plurality of adjacent teeth and the aforesaid supporting arm, the teeth being stamped into a hollow or shell-like configuration in order to give the same a natural rounded appearance with substantial depth or thickness, and the arm being left flat and thereby making the teeth yieldable and self-adjustable.

Signed at New York in the county of New York and State of New York this 18th day of Oct. A. D. 1932.

SAMUEL MARCUS.
